FACE GUARD FOR A HELMET

Fred R. Dunning, Brecksville, Ohio, assignor to Dungard, Inc., Brecksville, Ohio, a corporation of Ohio

Filed Sept. 9, 1966, Ser. No. 3,784

Term of patent 14 years

(Cl. D2—233)

I claim:

The ornamental design for a face guard for a helmet, as shown and described.
